UNITED STATES PATENT OFFICE.

ROBERT J. NORTHAM, OF LOS ANGELES, CALIFORNIA.

PAPER-CLIP.

1,019,348.

Specification of Letters Patent.

Patented Mar. 5, 1912.

Application filed March 6, 1911. Serial No. 612,627.

To all whom it may concern:

Be it known that I, ROBERT J. NORTHAM,
a citizen of the United States, residing in
the city of Los Angeles, county of Los An-
5 geles, State of California, have invented
new and useful Improvements in Paper-
Clips, of which the following is a specifica-
tion.

My invention relates to an improvement
10 in paper clips, consisting of a back board
upon which is mounted a spring actuated
jaw to hold letters or other papers upon the
board by confining them between the jaw
and the board and the object of my invention
15 is to provide a simple and convenient means
of automatically holding the jaw open at
different points of elevation, so that papers
may be adjusted or removed from the clip or
inserted therein with greater facility than
20 is possible in a clip where no means are pro-
vided for holding the jaw open when papers
are put into or taken out of the clip. I ac-
complish this object by the clip described
herein and illustrated in the accompanying
25 drawings in which,

23 drawings in which,
Figure 1 is a top plan of my improved
clip, with a bundle of papers in place there-
in. Fig. 2 is an edge elevation of the jaw
end partly in section of the parts shown in
30 Fig. 1.

In the drawings 5 is the back board and 6 is the spring actuated jaw of any approved construction of the ordinary paper clip. In the drawings I have shown a form of paper clip in which the spring which actuates the jaw is riveted to the back board by rivet 7, and is coiled around pintle bolt 8 as shown in dotted lines, thus connecting the two parts. At a central point in the jaw and in front of the pintle bolt, I cut an aperture 9 therein. Through this aperture projects a detent bar 10, which is preferably formed of sheet metal folded into U-shape and with the top flattened out to form a thumb piece 11. In the folded edge are cut or stamped a plurality of notches 12, which are adapted to catch the jaw and hold the same at whatever elevation the operator desires for the front end thereof. This elevation will usually depend upon the quantity of papers already in, or to be put into the clip. This detent bar is mounted in the end of a rocking arm 13, which is likewise preferably formed of sheet metal folded into U-shape. This rocking arm is rockably mounted on pintle bolt 8. A spring 14 is coiled around

rivet 15, which unites the detent bar to the rocking arm, one end of the spring bearing against the detent bar and the other end bearing against the rocking arm so as to 60 force the free end of the detent bar outwardly whenever the jaw is raised, thereby automatically causing the detent bar to engage the jaw. By this construction cheap and efficient means are provided for holding the jaw of the clip at a slight elevation above the papers to be put into or taken out of the clip. 65

Ordinarily in the operation of the device the operator will simply elevate the jaw to the first notch in the detent bar that will engage it and permit him to take a paper out of the clip or enable him to put papers into it. 70

If desired both the detent bar and the
rocking arm could be made of bar metal,
but I prefer the use of sheet metal and fold-
ing the same into a narrow **U** as the trough
formed by the metal enables me to easily
mount the spring which throws the free end
of the detent bar forward. 75 80

In the drawings I have shown four notches in the detent bar but there may be more or less as desired.

I have found in practice that it is desirable to have notches in the detent bar so as to hold it at many different elevations, because it requires less exertion to raise the jaw a short distance above the papers in the clip than it does to raise the jaw to the maximum height every time it is desired to take out of or put into the clip a paper. To release the jaw, the operator applies pressure to the thumb piece 11 and pushes it from beneath the jaw, when the jaw closes on the papers. 85 90 95

Having described my invention what I claim is:

1. A paper clip comprising a back board and a spring actuated jaw having an aperture therethrough; a pintle bolt connected with the base and upon which said jaw is rockably mounted; a rocking arm also mounted upon said pintle bolt; a spring actuated detent bar pivotally mounted in the outer end of said rocking arm, said detent bar having a plurality of notches in its outer edge and projecting through the aperture in said jaw, the notches being adapted to engage the edge of the aperture. 100 105 110

2. A paper clip comprising a back board and a spring actuated jaw having an aper-

ture therethrough rockably mounted on said back board, connecting means therebetween, a rocking arm formed of sheet metal bent into U-shape mounted upon the connecting means which connects the jaw to the back; a 5 detent bar formed of sheet metal bent into U-shape and having one end flattened and being provided with a plurality of notches and pivotally mounted on the rocking arm; 10 and passing through the aperture in the jaw and adapted to engage the jaw when actuated and hold the same in an elevated po-

sition; connecting means between said bar and arm; and a spring mounted on the connecting means of said bar and arm and 15 adapted to throw the free end of the bar away from the arm.

In witness that I claim the foregoing I have hereunto subscribed my name this 24th day of February, 1911.

ROBERT J. NORTHAM.
